DOOR ESCUTCHEON PLATE

Hunt Lewis, Arcadia, Calif., assignor to Schlage Lock
Company, a corporation

Application May 16, 1958, Serial No. 50,930

Term of patent 14 years

(Cl. D50—6)

FIG. 2

Fig. 1 is a front elevational view of a door escutcheon plate, the rear being identical, showing my new design.

Fig. 2 is an edge elevational view thereof.

I claim:

The ornamental design for a door escutcheon plate, as shown and described.
